DISPENSING POUCH FOR LIQUIDS

Justin M. Schmit, Pompano Beach, Fla., assignor to
Arctic Pac, Inc., Fort Lauderdale, Fla.

Filed Oct. 3, 1972, Ser. No. 294,536

Term of patent 14 years

Int. Cl. D9—05

U.S. Cl. D9—194

FIG. 1

FIG. 2

FIG. 3

FIG. 4

FIG. 5

FIG. 6

FIG. 1 is a perspective view of a dispensing pouch for liquids embodying my new design;

FIG. 2 is a side elevational view thereof;

FIG. 3 is a front elevational view thereof;

FIG. 4 is a rear elevational view thereof;

FIG. 5 is a top elevational view thereof; and

FIG. 6 is a bottom elevational view thereof.

I claim:

The ornamental design for a dispensing pouch for liquids, as shown and described.
